SEWING MACHINE ELEVATED WORK SUPPORT

Carl Gunnar Martinsson, Boras, Sweden

Application November 9, 1953, Serial No. 390,966

Claims priority, application Sweden April 15, 1953

1 Claim. (Cl. 112—260)

The present invention relates to sewing machines of the kind in which the shuttle mechanism of the machine is provided in the top of a pillar projecting upwards from the working table of the machine.

The object of the invention is to provide a device for sewing machines of the kind referred to for making possible the use of the tacking machine to fasten shoulder pads to the shoulder portions of garments, a work hitherto done by hand.

The invention is broadly characterised in that to the top of the pillar there is secured at a distance above the working table a substantially horizontal, slightly concave platform which is provided near its center with a hole in alignment with the pillar, the top surface of the latter being substantially flush with the top surface of the platform.

In a pillar sewing machine provided with such a platform the piece of work is given necessary support during the operation of fastening the shoulder pads thereto and the piece of work can be moved in all directions necessary for carrying out the work of fastening.

In the accompanying drawing there is diagrammatically shown an embodiment of the invention, and in said drawing:

Figure 1 is a side elevation of the head of the sewing machine and the pillar provided with a supporting platform (partly in section) according to the invention;

Figure 2 is a cross section through the supporting platform along the line II—II in Figure 1;

Figure 3 is a side elevation of the machine on a reduced scale; and

Fig. 4 is a perspective view of a sewing machine head and the present platform with a shoulder pad being attached to a piece of work.

In the drawing 1 denotes the working table of the sewing machine and 2 its overhanging arm to the free end 50 of which there is secured the machine head with a needle holder 5 and a presser foot 6. Beneath the head 4 there

2

projects upwards from the table 1 a pillar 7 of square cross section, which at its top contains the shuttle mechanism (not shown). To the top end of the pillar there is secured by means of brackets 8 a sheet metal platform 9 of a substantially rectangular, elongated shape and placed transversely in relation to the arm 2. The platform 9 which has bent-down, rounded edges 10, is slightly bowed in its longitudinal direction with the concave side so formed facing upwards.

10 The platform is provided at the top end of the pillar 7 with a rectangular hole 11 placed near the center of the platform.

To use the present apparatus for tacking shoulder pads to a piece of work such as the shoulder portion of a coat, the operator faces the head 4 of the sewing machine placing each shoulder pad with an attached piece of canvas on the top of the concave work support 9 and the coat shoulder thereover whereupon the shoulder is tacked to the pad and canvas by the sewing needle. The coat shoulder extends longitudinally of the work support and the operator has both hands free to smooth out the cloth and shape the shoulder portion for imparting the correct shape thereto.

The invention is not limited to the embodiment described and shown in the drawing but may be varied in detail without departing from the spirit of it. For instance the platform 9 can be made from other materials than sheet metal.

What I claim is:

30 In a sewing machine for tacking shoulder pads to a piece of work, an elevated work support comprising a pillar mounted on and extending from the working table of said machine towards the sewing needle thereof, a platform of sheet material having a substantially rectangular elongated shape and a central opening with said pillar extending through said opening with the free end of said pillar being substantially flush with said platform, means connecting said platform to said pillar with said platform positioned with its longitudinal direction extending laterally of the bracket-arm of the sewing machine and said platform having bent-down rounded edges and being slightly arcuate in its longitudinal direction with the resulting concave side facing towards said sewing machine needle.
